WASHING MACHINE

Fred A. Conterman, Jamestown, N. Y., assignor
to Jamestown Metal Equipment Company, Inc.,
Jamestown, N. Y., a corporation of New York

Application December 9, 1943, Serial No. 513,509

16 Claims. (Cl. 68—23)

1

This invention relates to improvements in washing machines of the type in which a single receptacle is utilized to both wash and centrifugally dry clothes.

In devices of this nature it is customary to provide a receptacle in which may be placed the clothes to be washed, rinsed, and dried. The receptacle includes a support on which it may revolve and, in some instances, the support includes an oscillating member directly connected with some form of agitator within the receptacle. During a washing operation, little or no vibration will occur due to the fact that such operation is effected by some form of oscillating agitator. However, in the operation of drying clothes it is necessary to rotate the receptacle at a high rate of speed and, since the clothes are never uniformly distributed within the receptacle, an unbalanced condition exists. This unbalance, even though relatively slight, develops a considerable vibration of the entire washing machine when the receptacle is rotated during a drying operation and results in a tendency of the machine to move or creep about, in addition to causing wear and breakage of many parts critically affected by such vibration. To overcome this difficulty, many ingenious vibration absorbing structures have been provided. However, since a laundry operation is invariably performed by persons untrained in mechanics, the washing machine is almost never filled to the same capacity, and any vibration absorbing device, to be satisfactory, would of necessity include some means for automatically varying the extent of vibration absorption, since such vibration varies with the speed of rotation of the receptacle and the extent to which it is loaded.

A serious problem in devices of this nature concerns the condition of the wash and rinse water. It is well known that soap commonly used in laundering operations combines, to some extent, with calcium or other minerals in the wash water, to form insoluble soap curds and that these curds, together with inorganic matter in the soiled clothes, present a considerable problem of disposal. For example, the soap curds and inorganic matter frequently are deposited as a film or coating on the interior walls of the receptacle, agitator and, in many instances, partially or completely block the receptacle drain. Additionally, the curds and inorganic matter are difficult to control in a device wherein the clothes are to be dried in the washing receptacle by using such receptacle as a centrifuge. Under these circumstances the clothes packing or bunching against the side walls of the receptacle act as a filter for

the wash water, leaving a residue of curds and inorganic matter on the clothes. To eliminate such deposits on the receptacle walls or clothes, various arrangements have been made by which to attempt to flush and remove, by overflow and drainage, the soap curds and inorganic matter prior to the centrifugal drying operation. This procedure is objectionable because of the inability to thoroughly flush the clothes, as well as requirement of a considerable additional quantity of hot water for a complete washing and drying operation.

5 The present invention is directed to and has for an object the provision of a washing machine of such construction and operative arrangement as to be capable of performing a complete operational cycle of washing, rinsing, and drying a quantity of clothes without the necessity of the operator handling these clothes from the time 10 the cycle of operation starts until it is completed.

15 It is also an object of the invention to provide structure by which vibration of the receptacle, during a clothes drying operation, is so reduced or neutralized as to be of no consequence.

20 Another important object of the invention resides in the provision of means by which the wash water may be caused to circulate during a washing operation and, while circulating, will be cleansed of a substantial quantity of soap curds 25 and inorganic matter.

25 Another object of the invention resides in the provision of a driving mechanism that is unital with respect to its support or suspension and serves as a counterbalancing weight mass for the clothes receptacle, particularly during the drying 30 operation.

35 The invention also includes the advantage of means for automatically obtaining a proper level of the wash water in the clothes receptacle and provision for reclaiming at least a part of the 40 wash or rinse water for re-use in a successive washing or rinsing operation.

45 Other objects and advantages of the invention will be more fully understood from a consideration of the following specification, taken in conjunction with the accompanying drawings; and in which

50 Fig. 1 is a vertical sectional view of a machine embodying one form of the invention with additional parts broken away, being taken substantially on the line 1—1 of Fig. 3;

Fig. 2 is a vertical sectional view taken substantially on the line 2—2 of Fig. 3;

Fig. 3 is a plan view of the machine;

55 Fig. 4 is a plan view of the clothes receptacle,

2

parts being broken away and sectioned to illustrate certain of the structural details;

Fig. 5 is a horizontal sectional view taken substantially on the line 5—5 of Fig. 2;

Fig. 6 is an enlarged fragmentary vertical sectional view of the mounting and support for the clothes receptacle and the entire drive mechanism;

Fig. 7 is an enlarged fragmentary plan view of the drive mechanism showing in greater detail and in section a part of the structure of Fig. 5;

Fig. 8 is a fragmentary vertical sectional view of the clutch mechanisms in position of engagement and disengagement reverse to that shown in Fig. 1;

Fig. 9 is an elevational view of a part of the structure located exteriorly of the machine and enclosed by a suitable channel member;

Fig. 10 is a plan view of the float devices located within the machine tub beneath the clothes receptacle;

Figs. 11 and 12 are fragmentary vertical and horizontal sectional views, respectively, of the connection between one of the float devices and the clothes receptacle control lever;

Fig. 13 illustrates one type of connection that may be employed as between the receptacle control lever and the receptacle drive mechanism;

Fig. 14 is an enlarged fragmentary plan view of a two-way valve structure shown in Figs. 1 and 9;

Fig. 15 shows in plan and elevation the operative position of a braking device for the receptacle; and

Fig. 16 shows in plan and elevation the inoperative position of the braking device of Fig. 15.

Referring more particularly to the drawings, the reference numeral 10 is employed to generally designate a washing machine embodying one form of the invention. The machine comprises a base 11, substantially circular in cross section. Reinforced portions 12 at the lower edge of the base mount suitable feet 13. These feet, as shown, are adjustable to level the machine. The upper edge or rim of the base portion 11 may be fitted with a gasket 14 that forms a combined seat and seal for the inwardly offset base 16 of a tub 17. The upper rim of the tub may, for convenience of assembly and use, be formed with an inwardly offset flange 18, on which is a gasket 19. This gasket serves to seat the flanged rim 21 of a top 22 to the machine. An aperture is made in the top 22, being closed by a cover 23 that may be of the contour and proportions shown in the drawings, and is mounted for pivotal movement on hinges 24. A suitable latch 26 on the cover serves to releasably engage it with the machine top 22.

The base 16 of the tub includes an upwardly and inwardly inclined central portion 27 that terminates in a flange 28 which defines a central opening. The base member 11 includes a support 29. This support is upwardly and inwardly inclined and includes an annular bottom flange 31, welded or otherwise suitably joined to the inside wall of the base member 11. The top of this support terminates in an annular flange or seat 32, having a rim 33 that defines a central opening 34. It will be noted that the annular flange 28 of the tub 17 rests on the seat 32, a suitable gasket 36 being interposed between these meeting surfaces. A saddle 37 is supported by its annular flange 38 on the flange 28 of the tub base 16, a suitable gasket 39 being interposed between these surfaces. Any suitable means may be em-

ployed to rigidly secure flanges 38, 28, and 32, such as the use of a ring 41, having threaded apertures with which studs 42 engage. The ring 41 may be permanently joined to the flange 32 and, as shown, the saddle flange 38 may be formed with an interior offset to receive the rim 33. The top 43 of the saddle is formed with a central opening 44. Mounted on the top 43 of the saddle is a rubber or other resilient ring 46. This ring may include permanently bonded top and bottom plates 47 and 48, the bottom plate 48 serving to anchor the heads of bolts 49 embedded in the ring. The bolts 49 project through suitable apertures in the saddle top 43 and are engaged by nuts 51.

Located within the base member 11 is a drive housing, generally designated by the numeral 52. This housing includes a portion 53 that terminates in a vertical tube-like extension 54. The lower end of a sleeve 56 is force-fitted into the upper end of extension 54. At its upper end, this extension is externally threaded, and beneath these threads is an annular shoulder 57. As shown in the drawings, the shoulder 57 forms a seat for an inner extension of the top plate 47 of the resilient ring 46, suitable pins 58 being provided to secure the extension 54 on center with the ring. The threaded portion of the extension 54 receives a supporting nut 59, above which is a lock-nut 61. On the upper end of the extension is a spacer sleeve 62 that, at its upper end, is of a reduced diameter to mount a liquid sealing ring 63. Interposed between the lower edge of the spacer sleeve 62 and lock-nut 61 is a sealing ring 64, parts of the sealing ring and sleeve being interfitted, substantially as shown. It will be noted that the inside diameter of sleeve 62 is substantially that of the inside diameter of the upper end of the housing extension 54, and sleeve 56 projects through and beyond the spacer sleeve. Pins 66 secure the spacer sleeve against rotation with respect to the housing extension. Mounted on the sleeve 56, directly above the upper end of spacer sleeve 62, is a bearing 67. An additional sleeve 68 serves to space bearing 67 from a further bearing 69. Above the bearing 69, the sleeve 56 terminates in an externally threaded portion with which a nut 71 is engaged. This nut, when turned down on the sleeve 56, draws together bearing 69, sleeve 68, bearing 67, spacer sleeve 62, and forces all of these elements downwardly of the sleeve 56 into abutment with the upper end of the housing extension 54. Projecting upwardly through the housing extension 54, and sleeve 56, is a drive shaft 72. The upper end of this shaft is splined, as at 73. It will be particularly noted that this shaft is of lesser diameter than that of the interior of the sleeve 56 and may be said to float with respect to this sleeve.

In the tub 17 is located a clothes receptacle 70. This receptacle comprises side walls 74 that may include a series of inner projections 76. The rim 77 of the receptacle may be rolled inwardly, substantially as shown, and beneath this rim the walls 74 are formed with openings 78, the number and diameter of which being predetermined for a purpose hereinafter more specifically described. The present disclosure of the invention shows the receptacle provided with a base 79, having a slight upwardly inclined area that terminates in a hub 81. If, as in the present showing, no separate agitator is provided, the hub 81 and base 79 may include attached or integral agitator blades 82. Adjacent the edge of the

base 79 is a flat area 83, trough 84, and depending rim or flange 86. The rim 86 is of a diameter to fit within the wall 74 of the receptacle, being secured thereto in any suitable manner, as by rivets 87. The rim 86 may either be of such thickness as to facilitate provision of vertical grooves which, when the receptacle is assembled, provide openings 88, or may combine with the wall 74 for this purpose. However, the number and size of the openings 88 is predetermined and bears a relationship hereinafter set out to the openings 78 in the side walls 74.

The hub 81 is of hollow construction and includes a depending annular rim 89 that encloses, without contacting, the spacer sleeve 62. Also the interior walls of this hub include a shoulder 91 with which the outer race or bearing 67 engages. Above the shoulder 91 is a further shoulder 92 which determines or limits downward adjustment of the bearings and associated parts on sleeve 56 when the nut 71 is rotated. It will be observed that the lower portion of the hub combines with spacer sleeve 62 and sealing ring 63 to provide an air pocket which serves to prevent penetration of water to the bearing 67.

A cap 93 includes a flange 94 mounted on the upper end of the hub 81 and is secured thereto by studs 96. A resilient sleeve 97 is bonded to the interior walls of the hub. A splined fitting 98 is bonded to the interior surface of the resilient sleeve 97 and engages the splined end 73 of the drive shaft 72. From the structure thus far described it is evident that the drive shaft 72 does not support any of the weight of the receptacle and contents, its sole purpose being to effect oscillation or spinning of the receptacle, as the case may be.

With the exception of the tube-like extension 54, the drive housing 52 is located entirely within the base 11, beneath the support 29, and derives its entire support through said tube-like extension 54. In other words, the drive housing, drive members located therein, etc., are suspended through the mounting of the extension 54 on the saddle 37. The lower portion of the housing includes a tubular member 99 that is joined along an upper flange 101 to the lower rim of the portion 53 in any suitable manner, as by studs 102. A lateral extension 103 of the tubular portion 99 mounts a gear 104. A cover plate 105 completes the enclosure for this gear and serves as a bearing for the gear shaft 106 which, above the cover plate, includes a crank arm 107. One end of a rod 108 is pivotally joined to the crank 107, the other end of this rod having pivotal connection, as at 109, with a member 111 of a jaw clutch 110. The lateral extension 103 includes an offset depending portion 112 in which is located a shaft 113. This shaft, beneath the portion 112, mounts a pulley 114, and within the housing extension 103, mounts a gear 116 that meshes with gear 104.

The shaft 72, at its lower end and beneath the drive housing structure above described, is splined, as at 117, and mounts a drive shoe 118 that forms part of a friction clutch 120. A spring 119 and lock plate 121 provide yielding pressure engagement of the surface 122 of the shoe with a corresponding surface 123 of a balance wheel 124. This wheel may be centrally recessed to receive the drive shoe 118 in substantially the manner shown, and includes a hub portion 126 on which is formed a pulley 127. The pulley 127 is in horizontal alignment with pulley 114. Above the shoe 118, the shaft 72 is provided with a bushing 128 that is fitted in one end of a sleeve

129. Sleeve 129 is carried by the tubular portion 99 of the drive housing and the hub 126 is mounted on this sleeve for relative rotation through a suitable bearing 131. Above and below this bearing are collars 132 and 133, the upper collar being pinned to the tubular portion 99, and the lower collar being held in place by a nut 134 engaged with the lower end of the sleeve 129. Suitable top and bottom fluid seals 136 may be provided as shown.

The upper end of sleeve 129 projects into the portion 53 of the drive housing and is internally fitted with a bushing 137. This last mentioned sleeve engages the shaft 72 and, together with bushing 128, provides the entire bearing support for shaft 72. Externally of the upper end of sleeve 129 is a further bushing 138 which mounts the part 111 of jaw clutch 110. A suitable bearing ring or its equivalent 139 may be mounted on the sleeve 129 between the part 111 and the upper end of the tubular housing 99. As is common in jaw clutches, the part 111 on its upper rim is provided with a series of teeth 141.

The other part 142 of the jaw clutch includes teeth 143 engageable with teeth 141. The hub 144 of this portion of the clutch is pinned to the shaft 72. Above the hub 144 is a bearing 146 that mounts a collar 147. The upper end of the collar 147 is closed and sealed by a cap ring 148 pinned to the shaft 72. A pair of diametrically opposed stub shafts 149 mount corresponding ends of arms 151 of a yoke 152. Extensions 153 mount the yoke 152 for swinging movement through a pin 154 carried by lugs 156 on one side wall of the portion 53 of the housing. It will of course be understood that this side of the housing 53 is suitably apertured for this purpose, through the web portion 157 of yoke 152. A tension spring 150 is connected between yoke 152 and a suitable fastening on housing 53 to urge the yoke in a downward direction and aid in meshing clutch jaws 143 and 141.

Adjacent the collar 147, the housing portion 53 is provided with a boss 161 that mounts a pair of parallel proximate pins 162. These pins support corresponding ends 163 of a pair of semi-circular brake-shoes 164. The free ends 166 of these shoes include pins 167 connected by a spring 168. This spring yieldingly urges the shoes into a position such that the lining 169 thereof will engage the drum 171 formed on the part 142 of the jaw clutch. The portion 53 of the housing includes a boss 172 fitted with a sleeve 173 through which a shaft 174 projects. Mounted on the inner end of this shaft is a cam 176. The end of the shaft beyond the cam is fitted with a spreader pin 177 which projects between the free ends 166 of the brake-shoes. This pin, in one rotative position of shaft 174, holds the shoes out of contact with the drum 171, whereas in the other rotative position of this shaft, the pin frees the shoes for contact with the drum, under a pressure determined by the spring 168. Shaft 174 is coupled with a shaft 178 through a tubular member 179. This shaft is supported in a bushing 181 secured to the side wall of the base 11 directly beneath the inclined wall of the support 29. Bushing 181 also mounts one end of an adjustable strap 180. Secured to the outer end of this shaft is a pulley 182 that is engaged by a belt 183. As may be observed from an examination of Figs. 1 and 3, the washing machine includes substantially full length front and rear channel members 184 and 186, respectively. Channel member 184 is secured in any suitable manner to the machine and,

as shown in Fig. 1 of the drawings, cooperates with the upper end of strap 180 to mount a pin 181. Exterioly of the member 184, the pin carries an operating lever 188 and within this member the pin mounts a pulley 189 that is also engaged by the belt 183. To prevent lost motion, the belt may be pinned, as at 191, to pulleys 182 and 189. Movement of the lever 188 from a vertical toward a horizontal position rotates shaft 174, changing the position of cam 176 and either expanding the brake-shoes 184 or allowing them, under tension of spring 168, to engage the drum 171. Enclosed by the channel member 184, and located slightly beneath and to one side of the pulley 189, is a structure by which to lock operating lever 188 in a neutral or inoperative position, should certain conditions of operation of the machine not be met. This mechanism includes a collar 192 secured to the wall of the tub 17 and in which is mounted a pin 193. This pin supports one end of an arm 194, to the other end of which is attached a liquid-level float 196. The pin 193 extends to one side of the collar 192 and is fitted with an arm 197, on the free end of which is a shoulder or ledge 198. A pin 199 cooperates with the ledge 198, as follows: Should water in the tub 17 attain a greater than desired level for the operation of spinning the receptacle 73, float 196 will be raised, and through pin 193 and arm 197, will cause the ledge 198 to move into a position beneath the pulley pin 199. Thus, the operating lever 188 cannot be rotated in a direction to start the receptacle spinning. Mounted within the channel member 184, above the lever 188, is a switch box 201 fitted with a suitable knob 202 and serves to start and stop operation of the machine.

Attached to the portion 53 of the drive housing 52 by means of a bracket 203 is a motor 204. This motor is disposed vertically and includes a drive pulley 206 so located as to be in operative alignment with pulleys 114 and 127. For proper suspended weight distribution about the portion 53 of the housing, the motor 204 is located substantially opposite the housing extension 103. Further mention of this will be made following description of other parts associated with and suspended by the housing portion 53.

Substantially opposite the shaft 174 that controls operation of the jaw clutch, the flange 101, attached to the housing 53, mounts a laterally offset arm 207 that terminates in a vertical boss 208. This boss is drilled to receive pin 209 which in turn pivotally mounts a pair of arms 211 that form part of a tubular member 212. The member 212 on its upper end mounts a pump 213 which includes a shaft 214 located within this member. The lower end of this shaft is fitted with a pulley 216, whereas the upper end mounts the pump impeller blades 217. A cover plate 218 closes the top of the pump 213 and includes a hose or flexible tube connection 219. An arm 221, joined to or integral with the tubular member 212, provides connection for one end of a spring 222. The other end of this spring is attached to a bracket 223 on the housing 53 and urges the pump in a circular path about the pin 209 in a counter-clockwise direction, as viewed in Fig. 5 of the drawings. Pulley 216 is also in operative alignment with motor pulley 206 and pulleys 114 and 127, and an endless belt 224 or other drive means engages these pulleys in the manner indicated in Fig. 5 of the drawings. It will be observed that the belt 224, on leaving the motor pulley 206, passes directly over pulley 114, then around pump pulley 216, thence around pulley 127, returning to the

motor pulley 206. The position of the pump is such that it serves, through spring 222, as a tightener for the belt 224.

Located in the lowermost portion of the base 16 of the tub is a drain that includes a collar 226. The collar extends beneath the base and may be fitted with and supports a trap 227. This trap at one end includes a hose or flexible tube fitting 228 and a hose 229 connects fitting 228 with the pump fitting 219. In this manner water within the tub 17 may be withdrawn by the pump.

The base 11, adjacent the pump 213, is apertured to receive a two-way valve structure 231 that includes an outlet or drain pipe 232, a further outlet connection 233, and a flexible hose connection 234. A hose 236 connects the pump 213 through fitting 237 with the two-way valve 231. This valve, as shown in the drawing, includes a stopper 238 mounted for swinging movement on a shaft 239. With the stopper 238 in the position shown in Fig. 5, water withdrawn from the tub 17 through the pump 213 will pass into the connection 233; whereas, if the stopper is moved to close outlet 233, water withdrawn from the tub will pass out through the drain pipe 232. To assure proper seating of the stopper 238 in position to close either of the outlets 232 or 233, a spring toggle is provided. This includes a member 241 that at one end has a collar 242 mounted on the upper end of shaft 239. The other end of the member 241 mounts a pin 243. An extension 244 of this valve housing mounts a pin 246. This pin supports one end of a plate 247 having an elongated slot through which shaft 239 projects. This pin mounts one end of a spring 248, the other end of the spring being joined to pin 243. Thus, when shaft 239 is turned to shift the stopper, spring 248 exerts pressure to hold the stopper in the chosen closed position.

It will be noted that a part of the housing of the two-way valve 231 extends beyond the lateral limits of the base 11 and the channel member 186 serves to enclose this structure, together with other parts connected therewith. Furthermore, this channel member is preferably similar in size and appearance to the channel member 184 and is preferably located diametrically opposite, substantially as indicated in the drawing, thus providing uniform and balanced enclosures for those parts necessarily located exteriorly of the base 11 and tub 17.

The upper end of the channel member 186 extends over the top of the machine to form an enclosure 251. A shaft 252 constitutes an upward continuation of the shaft 239, being coupled thereto through the collar 242. This shaft terminates in a valve handle 253 located above the enclosure 251. The outlet 233 of the two-way valve 231 connects with a vertically extending pipe 254 located in the channel member 186. This pipe projects horizontally through a suitably framed opening in the curved portion of the top 22 into the top interior of the tub 17. As may be seen in Figs. 2 and 3 of the drawings, the horizontal extension 256 terminates in an outlet member 257. This member is attached to the top 22 at substantially its center, the cover 23 (see Fig. 3) being contoured to provide for this. Depending from the member 257 is a resilient bell 258. This bell encloses the cap 93 that is mounted on the hub 81 within the receptacle 73.

Projecting into the enclosure 251 are conventional hot and cold water pipes 260 and 259. These pipes terminate in a mixing chamber 261. Associated with this chamber is a water actuated

control valve 262. From the control valve 262 a pipe 263 connects with the outlet member 257. The water control valve 262 includes a plunger rod 264 which extends downwardly within the channel member 186 to a point beneath the base of the receptacle 13. This rod is enclosed substantially throughout its length within a tubular member 266 which is secured at its upper end to the tub wall by a bracket 267, and at its lower end terminates in a housing 268. This housing opens into the interior of the tub 17 and pivotally mounts one end of an arm 269. The free end of this arm lies within the tub and mounts corresponding ends of rods 271. These rods are bent to conform to the tub contour and, at their free ends, floats 272 are provided. As is evident from Figs. 1 and 10 of the drawings, floats 272 are effected by water contained in the lower part of the tub 17, beneath the receptacle 13. With no water in the tub, floats 272 assume the position shown in Fig. 1, whereas as the water level rises these floats move upwardly, causing arm 269 to move upwardly and raise plunger 264. Upward movement of the plunger serves to close valve 262, thus shutting off the water supply from the mixing chamber 261.

The enclosure 251, as may be seen in Figs. 1 and 2 of the drawings, includes an inclined plate 273 on which are mounted hot and cold water control handles 274. These handles are adjacent the lever 253 which controls the direction of flow of water in the circulation system during various uses of the machine. The plan view of Fig. 3 clearly shows that motor switch 202, receptacle control lever 188, handle 26, and the controls on the enclosure 251 are all conveniently available to an operator from the front of the machine.

Having described the structural parts of the invention, a complete cycle of operation is set forth in order that the inventive features may be more fully understood. It is assumed that a quantity of materials to be washed have been placed in the receptacle 10. Lever 253 occupies the position indicated as "Wash" and, since this lever controls the valve structure 231, drain pipe 232 will be closed and connection 233 open. The switch 202 may be turned to start operation of the motor 204. However, since the lever 188 is in neutral position, operation of the motor neither causes the receptacle to oscillate nor spin. No disconnection being necessary in the present setup, the water pump 213 functions with operation of the motor.

The desired combination of hot and cold water may be obtained by turning the control handles 274. This permits passage of water from any conventional source of supply into the mixing chamber 261. The normal water pressure of the system causes valve 262 to open, thus holding rod 264 in depressed position and allowing water to pass through the primary line 263, outlet member 251, and bell 258 into the receptacle 13. As water flows into the receptacle at a rate determined by the valve 261, a part of it passes therefrom through openings 88 into the lower part of the tub 17, from which it is withdrawn through the drain 226 by the pump 213 and passes through valve 231, pipe 254, secondary line 256, and returned to the receptacle through bell 258. Inasmuch as the flow of water through openings 88 is less than the flow into the receptacle, the receptacle becomes filled and a further flow from the receptacle then takes place through openings 78 in the side walls thereof. From this point on during the operation preliminary to washing,

water, by passing both from openings 78 and 88, starts filling the base of the tub, thus raising floats 272 to a position such that arm 269 raises rod 264 and closes valve 261. Closing this valve 5 shuts off any further supply of water from the main hot and cold water lines 258 and 259. A desired quantity of soap having been placed in the now filled receptacle, cover 23 is closed and secured by latch 26, and lever 188 rotated in a 10 direction to rotate cam member 176 to permit spring actuation of yoke 152 to engage the teeth of the jaw clutch 110. Prior to this, and from the time of turning on the switch 202, the motor has not only been actuating the pump 213, but also caused the balance wheel 124 to rotate at a predetermined speed.

Engagement of the jaw clutch connects drive shaft 72 with the oscillating mechanism and thus the receptacle 10 is set in motion in a manner to 20 produce washing agitation. During the entire washing operation, pump 213 is operating to effect circulation of the water; that is, water is constantly passing out of the openings 88 into the base of the tub, through trap 227 and thence again into the receptacle through the secondary pipe 256. It will be noted that the bottom edge of the water egress bell 258 is well below the normal washing water level determined by receptacle openings 78, for the purpose of preventing an abnormal amount of suds foam accumulating on the top of the water surface in the receptacle. It is well known that soapy water, when moved under pressure, will burst into foam when ejected into the atmosphere, and the location of the bottom edge of bell 258 acts as a preventative. Of course as inorganic matter is freed from the materials being washed, such matter will be caught in the trap 227 and the water returning to the receptacle 10 will be free of such matter. Thus, during the washing operation a large percentage of inorganic matter is completely removed from the wash water and the trap 227 materially assists in reducing the amount of subsequent rinsing necessary.

On the completion of the washing operation, the lever 188 is returned to a position to disengage the jaw clutch and stop oscillation of the receptacle. Such movement of the lever 188, 40 however, does not stop operation of the pump 213, and if it is desired to immediately dry the material within the receptacle, the lever 253 is rotated to the position marked "Drain." The pump now effects withdrawal of the water from the tub into the drain 232. When the receptacle 50 10 and the tub 17 are substantially free of water, the lever 188 may be rotated in a direction opposite that from which it was rotated to engage the jaw clutch. This movement of the lever causes cam 176 to move the collar 147 and drive shaft 72 upwardly. Such upward movement of the shaft engages the friction clutch by moving the drive shoe 118 into a position such that the surface 122 thereof engages surface 123 of the balance wheel, the engagement of these surfaces being yieldable to an extent determined by the spring 119. Of course a measure of slippage occurs between the surfaces 122 and 123 during the period that the receptacle is accelerating to a spinning speed sufficient to dry the materials therein. The wet material in the receptacle is of considerable weight, and only a slow pickup to spinning speed would be possible with a motor of conventional size were it not for the fact that 60 the balance wheel, being in motion, assists the

11

motor during this period in producing an extremely rapid acceleration.

During the spinning operation, water extracted from the material within the receptacle leaves the receptacle through the openings 78 and 88, passing into the base of the tub from which it is withdrawn by the pump to the drain pipe 232.

On completion of the spinning operation, the lever 188 is again rotated to a neutral position, thus disengaging the clutch surfaces 122 and 123, and as the cam 176 is rotated to effect disengagement of these clutch plates, the shaft on which it is carried rotates spreader pin 177 in a direction to allow brake-shoes 164, under tension of spring 168, to engage the drum 171 of the member of the jaw clutch pinned to the shaft 72. The effect of this braking action is to so rapidly terminate rotation of the receptacle 70 that should an operator of the machine inadvertently move the lever 188 beyond neutral position, and partially or wholly into a position to engage the jaw clutch, no damage would occur. The spreader pin 177 operates to hold the brake-shoes 164 out of engagement with the drum 171 during both oscillation and spinning of the receptacle. It, of course, should be understood that when the machine is not in operation and the lever 188 is in neutral position, the brake-shoes are always in contact with the drum 171. Thus, during filling and emptying the receptacle it is held against inadvertent rotation.

It is obvious that the tub 17 should not contain water to a level above the base of the receptacle at the beginning of or during the spinning operation, and should the trap become plugged, or a water shut off valve fail to function, this might occur were it not for the provision of the protective mechanism in the form of float 196 that is associated with the lever 188. Should the level in the base of the tub rise above the level normally controlled by floats 272, float 196 will be raised and in so doing projects the ledge 198 of an arm 197 into the path of pin 199 carried by the pulley 189, and in consequence the lever 188 cannot be rotated in a direction to set the receptacle spinning but may be rotated in a direction to set the receptacle oscillating.

After the first spinning or extraction operation has been completed, the clothes may be rinsed by repeating the washing operation as above, using only clear water without soap, or, by proper manipulation of mixing and drain valves, rinsing may be accomplished during the extraction period. The number of rinses or method of rinsing is optional with the operator. It is also possible, at the option of the operator, through proper manipulation of controls, to collect and save a portion of the rinse water in the tub 17 for use in washing the next batch of clothes. The relationship of the size and number of openings 88 in the receptacle to the capacity of pump 213 is such that the water may be transferred from tub 17 to the receptacle 70, and it is only when the water level in the receptacle has reached the openings 78 that a balanced condition can be maintained. In order to reach this balance, make-up water is added through the mixing valve.

Particular attention is directed to the fact that the receptacle 70 and the entire mechanism for both oscillating and spinning it are resiliently supported at a point well above the center of gravity of this entire group of parts. Any unbalanced weight in the receptacle, such as wet clothes unequally distributed, will be compe-

12

sated for by the gyroscopic action of the rotating balance wheel and the fixed mass of the remainder of the drive mechanism, as, for example, motor, oscillating drive, water pump, housing, etc. The only unbalance in the system being in the receptacle at or near its base and close to the point of suspension, assures the weight mass, both revolving and stationary, being more than adequate to dampen or completely eliminate vibration of an unbalanced load in the receptacle.

From the foregoing it will be evident that the present invention not only utilizes a single receptacle for washing, rinsing and drying operations and provides for constant water circulation and purification, but also provides an entirely suspended drive mechanism serving as a counterbalance to reduce or altogether eliminate machine vibration common to oscillating or rotating receptacles having an unequal load distribution. It will also be evident that the structural parts are greatly simplified as to their number and ease of assembly.

Although applicant has shown and described only one form of his invention, it will be apparent to those skilled in the art that modifications or adaptations of the structure may be made and are considered as being within the scope of the invention insofar as they are defined in the annexed claims.

Having thus set forth my invention what I claim as new and for which I desire protection by Letters Patent is:

1. In a washing machine, a rotatable receptacle, a drive mechanism, a housing for said mechanism including an extension adapted to support said receptacle, a drive shaft projecting through said housing and extension and having operative engagement with a hub in said receptacle, a clutch for operatively associating said shaft with an oscillating part of said mechanism, a further clutch for operatively associating said shaft with a rotating part of said mechanism, and means for effecting axial movement of said shaft to selectively engage said jaw clutch and said further clutch.

2. In a washing machine, a rotatable receptacle, a drive mechanism, a housing for said mechanism including an upper extension mounting said receptacle, a lower extension of said housing mounting a rotatable balance wheel, a drive shaft

projecting through said housing and extensions

and having permanent operative engagement

with said receptacle, clutches for operatively as-

sociating said shaft with an oscillating part of

said mechanism and with said balance wheel,

and motive means for operating said mechanism

and said balance wheel.

3. In a washing machine, a rotatable recep-

tacle, a drive mechanism, a housing for said mechanism including upper and lower aligned ex-

tensions, a balance wheel carried by the lower

extension, the upper extension serving to mount

said receptacle, a drive shaft projecting through

said housing and extensions and having operative

association with said receptacle, clutches for op-

eratively associating said shaft in a selective

manner with an oscillating part of said mecha-

nism and with said balance wheel, and motive

means operatively associated with said balance

wheel and said mechanism.

4. In a washing machine, a rotatable receptacle,

a drive mechanism, a housing for said mech-

anism, an upper extension of said housing mount-

ing said receptacle, a drive shaft projecting

through said housing and having permanent op-

erative association with said receptacle, a bal-

ance wheel carried by a lower extension of said housing, motive means for said balance wheel and said mechanism, clutches selectively operable to operate said shaft through said mechanism and said balance wheel, and brake means operable to prevent rotation of said shaft when said clutches are in an inoperative position.

5. In a washing machine, a rotatable receptacle, a drive housing having an upper extension mounting said receptacle, a balance wheel carried by a lower extension of said housing and having operative association with suitable motive means, a drive shaft having permanent operative association with said receptacle, clutch means carried by said shaft and operable by axial movement of said shaft to effect rotation of said receptacle through said balance wheel, and brake means operable to prevent rotation of said receptacle when said clutch means is rendered inoperative.

6. In a washing machine, a rotatable receptacle, a drive housing having an upper extension mounting said receptacle, a balance wheel carried by a lower extension of said housing and having operative association with suitable motive means, a drive shaft operatively associated with said receptacle, clutch means carried by said shaft, said means in operative position transmitting rotation of said balance wheel to said receptacle, brake means operable on said shaft to render said receptacle non-rotatable, said brake means being so associated with said clutch means as to become inoperative when said clutch means is rendered operative.

7. In a washing machine having a rotatable receptacle, a support for said receptacle, a drive mechanism located beneath said receptacle carried by said support, a drive shaft projecting thru said mechanism into said receptacle and having operative association therewith, a balance wheel remote from said receptacle, said wheel being continuously operable during operation of said machine, clutch means for operatively associating said shaft with said balance wheel, and means resiliently mounting said support at a point above said mechanism and beneath said receptacle.

8. A washing machine comprising an enclosure, a rotatable clothes receptacle in the upper portion of said enclosure, a drive mechanism for rotating said receptacle, said mechanism being located beneath and having its vertical center substantially on center with the vertical center of said receptacle, a support member for said receptacle and said mechanism, means carried by said enclosure resiliently suspending said member at a point intermediate said receptacle and said mechanism, a rotatable balance wheel remote from said receptacle, means operatively connecting said balance wheel directly with said mechanism, and other means selectively operable to operatively connect said receptacle with said balance wheel, the combined weight of said mechanism, balance wheel and member beneath the resilient mounting means being greater than the weight of said receptacle and any contemplated clothes contents.

9. In a washing machine, a rotatable receptacle, a housing mounting a drive mechanism, an extension on said housing serving as a support for said receptacle, a drive shaft projecting through said housing and extension and having operative engagement with said receptacle, means carried by a part of said housing mounting said shaft for axial movement, and means for axially moving

said shaft into operative association with an operating part of said mechanism.

10. In a washing machine, a rotatable receptacle, a drive mechanism, a housing for said mechanism, a drive shaft projecting through said housing and having permanent operative engagement with said receptacle, a rotatable balance wheel carried by the lower end of said housing, clutches for operatively associating said shaft with an oscillating part of said mechanism and with said balance wheel, and motive means for operating said mechanism and said balance wheel.

11. In a washing machine having a rotatable receptacle, a support for said receptacle, a drive mechanism located beneath said receptacle carried by said support, a drive shaft having operative association with said receptacle, a balance wheel remote from said receptacle, motive means for operating said mechanism and rotating said balance wheel, and clutch means for operatively associating said shaft with said balancing wheel.

12. In a washing machine, a rotatable receptacle, a drive housing having an upper extension mounting said receptacle, a balance wheel carried by a lower extension of said housing and having operative association with suitable motive means, a drive shaft operatively associated with said receptacle, clutch means, said means in operative position transmitting rotation of said balance wheel to said receptacle, brake means operable on said shaft to render said receptacle non-rotatable, said brake means being so associated with said clutch means as to become inoperative when said clutch means is rendered operative.

13. In a washing machine, a rotatable receptacle, a housing mounting a drive mechanism, an extension of said housing serving as a support for said receptacle, a non-load carrying drive shaft projecting through said housing and extension and having operative engagement with said receptacle, means carried by a part of said housing mounting said shaft for axial movement, clutch means for axially moving said shaft into operative association with an operating part of said mechanism, and brake means operable on said shaft to render said receptacle non-rotatable when said clutch means is inoperative.

14. A washing machine comprising an enclosure, a rotatable clothes receptacle in said enclosure, a drive mechanism for said receptacle, a shaft for transmitting rotary motion to said receptacle, means providing resilient support for said receptacle and said mechanism at a point above their combined weight mass, rotatable means remote from said receptacle operably interposed between said drive mechanism and said shaft, and clutch means operable to connect said receptacle with said rotatable means through said shaft.

15. A washing machine comprising an enclosure, a rotatable clothes receptacle in said enclosure, a drive mechanism for rotating said receptacle, a shaft for transmitting rotary motion to said receptacle, means providing resilient support for said receptacle and said mechanism at a point above the center of their combined weight mass, constant speed means adapted to be continuously operable by said drive mechanism, and clutch means for operatively connecting said constant speed means with said receptacle through said shaft in a manner to gradually accelerate rotation of said receptacle to the speed of said constant speed means.

16. In a washing machine having an enclosure, a rotatable receptacle in said enclosure, a housing,

15

a drive mechanism mounted in said housing, an extension on said housing projecting into said enclosure, a drive shaft projecting through said housing and extension and having operative engagement with said receptacle, means providing resilient support for said housing, drive mechanism, and receptacle, further means mounting said drive shaft for axial movement, and still other means for axially moving said shaft into operative association with an operating part of said drive mechanism whereby to effect operation of said receptacle.
